UNITED STATES PATENT OFFICE.

GOTTLIEB SCHNEIDER, OF BLUFFTON, INDIANA, ASSIGNOR OF ONE-HALF TO SEYMOUR ROBINSON, OF BLUFFTON, INDIANA.

CLOTHES-DRIER.

959,888.

Specification of Letters Patent.

Patented May 31, 1910.

Application filed November 6, 1909. Serial No. 526,576.

To all whom it may concern:

Be it known that I, GOTTLIEB SCHNEIDER, a citizen of the United States, residing at Bluffton, in the county of Wells and State 5 of Indiana, have invented a new and useful Clothes-Drier, of which the following is a specification.

This invention relates to clothes driers of that type in which a single standard is provided with radial arms constituting supports for a line from which the clothing can 10 be suspended.

One of the objects of the invention is to provide a device of this character having 15 a base designed to be anchored at a predetermined point, and which is provided with means for detachably engaging the removable portion of the drier so as to support said drier in operative position, it being 20 possible to readily disconnect the body portion of the drier from the base so as to permit it to be stored away when not in use.

Another object is to provide a drier the radial arms of which may be simultaneously 25 folded against the supporting standard so as to occupy the minimum amount of space when the device is not in use.

Another object is to provide improved 30 means for supporting the arms while extended.

A still further object is to provide a line which is so mounted within the arms as to become taut throughout the length thereof 35 when the arms are opened out from the standard, said line being threaded through the arms and preferably arranged to form squares.

With these and other objects in view the 40 invention consists of certain novel details of construction and combinations of parts hereinafter more fully described and pointed out in the claims.

In the accompanying drawings the preferred form of the invention has been 45 shown.

In said drawings, Figure 1 is a side elevation of a clothes drier embodying the present improvements, the same being shown with the arms extended outwardly from the 50 standard. Fig. 2 is a view partly in section and partly in elevation of the drier folded, the same being removed from the base and a portion of the standard being broken away. Fig. 3 is a plan view of the drier 55 with the parts in the positions shown in Fig.

1. Fig. 4 is a perspective view of the base. Fig. 5 is a similar view of the lower end of the standard.

Referring to the figures by characters of reference, 1 designates a base plate having a central depending stem 2 designed to be embedded within a concrete base 3 or the like, there being a central stud 4 upstanding from the disk 1 and equidistant between opposed, oppositely extending angular retaining ears 5 which are formed integral with the base 1. Locking pins 6 are removably mounted within the base 1 at opposite sides of each of the ears 5 and are for the purpose hereinafter set forth.

The standard 7 of the drier is preferably tubular and the lower end thereof is designed to receive the stud 4, there being a collar 8 secured to the lower end of said standard and provided with oppositely extending wings 9 which, after the pins 6 have been removed, are capable of swinging into position beneath the ears 5 and of fitting snugly thereunder. By replacing the pins 6 within the base 1, the wings 9 will be 80 locked in engagement with the ears 5 and the standard 7 thus held perpendicularly to the base.

A sleeve 10 is adjustably mounted on the standard 7, it being held in any desired position, by means of a set screw 11. An annular shoulder 12 is formed upon the upper end of the sleeve 10 and a ring 13 is mounted to rotate upon this sleeve and below the shoulder, said ring being provided with an 90 outstanding stud 14 for the purpose hereinafter set forth.

A stem 15 is mounted to slide and rotate within the standard 7 and a set screw 16 is employed for locking this stem against 95 movement within the standard. A collar 17 is secured to the stem 15 and has pairs of ears 18 extending radially therefrom, the ears of each pair being connected by a stop strip 18' which can be secured thereto or 100 formed integral therewith. An arm 19 is pivotally mounted between the ears of each pair, and is designed, when swung downward to a predetermined angle, to rest upon the stop strip 18'. A sleeve 20 is slidably 105 mounted on the stem 15 and has ears 21 extending therefrom, these ears being connected, by means of rods 22, with the respective arms 19, the said rods being pivotally connected both to the arms and to the 110

ears 21. An actuating rod 23 is secured to the sleeve 20 and extends downwardly to a point below the collar 17, there being an eye 24 at the lower end of this rod and which is designed to be placed in engagement with the stud 14 heretofore referred to.

A series of transverse openings 25 is formed in each of the arms 19 and a rope 26 is threaded through the openings. One length of rope is preferably utilized, said rope being extended through the innermost openings of the arms 19 and being provided with a terminal loop 27 through which the rope extends after passing through the last one of these apertures. The said rope is then extended alongside one of the arms 19 to the next adjoining opening and thence through the several arms and back to said opening after which it is extended along the arm to the next opening. This arrangement is followed until the rope has been passed through all of the openings after which the end thereof is secured as indicated at 28. It will therefore be seen that, inasmuch as the rope is slidably mounted in the openings in all of the arms, and is continuous, when the arms 19 are swung outwardly and downwardly all of the strands of the rope will be drawn taut simultaneously.

30 A stop pin 29 is preferably extended through the stem 15 so as to limit the downward movement of the sleeve 20.

In using the device herein described the stem 2 is embedded within a concrete base 35 or the like, or, if preferred, the base 1 can be secured to a roof or other structure in any other preferred manner. The pins 6 are disengaged from the base 1 and the tubular standard 7 is placed on the stud 4 after 40 which said standard is partly rotated so as to bring the wings 9 into position beneath the angular ears 5. The pins 6 are then replaced in the base 1 and the wings are thus locked upon the base. The standard 7 will 45 therefore be held fixedly in an upstanding position and the length of the standard can be increased or diminished by loosening the set screw 16 so as to permit the stem 15 to be shifted longitudinally. It is of course 50 necessary to also loosen the set screw 11 so as to allow the necessary longitudinal movement of the sleeve 10 upon the standard. After the parts have been adjusted, the rod 23 is pulled downwardly and sleeve 55 20 is therefore moved therewith and motion is transmitted therefrom through the rods 22 to arms 19 which are swung outwardly and downwardly so as to bring the rope 26 taut. Upon the completion of the downward movement of arms 19, the eye 24 is 60 placed in engagement with stud 14, it first being necessary to so adjust the sleeve 10 as to bring this stud into position to be engaged by the eye. The parts are therefore locked in their proper positions and

fabrics can be suspended from the rope without causing any of the arms to fold upwardly against the stem 15.

When it is desired to remove the drier, as when the same is not in use, the stem 23 is 70 disengaged from stud 14 and pushed upwardly. This will cause the arms 19 to fold against the stem 15. Pins 6 can then be disengaged from base 1 and the standard rotated so as to move the wings 9 out of 75 engagement with ears 5. The entire drier can then be lifted off the base and carried to any point where it is desired to store it.

Various changes can of course be made in the construction and arrangement of the 80 parts without departing from the spirit or sacrificing any of the advantages of the invention.

What is claimed is:—

1. In a clothes drier, the combination 85 with a standard, of a stem slidably and revolvably mounted therein, a series of arms pivotally connected to the stem and extending radially therefrom, a sleeve slidably mounted on the stem, pivotal connections 90 between the sleeve and the arms, means for shifting the sleeve, and revoluble means upon the standard for engaging said shifting means to lock the sleeve and arms in a predetermined position.

2. A clothes drier including a standard, a stem revolvably and slidably mounted therein, means for locking the stem against movement within the standard, arms pivotally connected to the stem and extending 100 radially therefrom, a sleeve slidably mounted on the stem, pivotal connections between the sleeve and arms, an actuating rod connected to the sleeve, a sleeve adjustably mounted on the standard, a ring mounted 105 for rotation on said adjustable sleeve, and means upon the ring for detachably engaging the rod to lock the slidable sleeve and arms in predetermined positions.

3. A clothes drier comprising a base, a 110 standard detachably connected thereto and supported thereby, a stem adjustably connected to the standards, said stem being revolvable within the standard, arms pivotally connected to the stem and foldable there- 115 against, slidable means connected to the arms for simultaneously shifting the same toward or away from the stem, means for actuating said slidable means, and a locking device revolvable upon the standard and detachably engaged by said shifting means to hold the arms in predetermined positions.

In testimony that I claim the foregoing as my own, I have hereto affixed my signature in the presence of two witnesses.

GOTTLIEB SCHNEIDER.
